UNITED STATES PATENT OFFICE.

SIEGFRIED ROSENZWEIG, OF NEW YORK, N. Y.

VALVE-GEAR.

1,323,788.

Specification of Letters Patent.

Patented Dec. 2, 1919.

Application filed December 20, 1918. Serial No. 267,620.

To all whom it may concern:

Be it known that I, SIEGFRIED ROSENZWEIG, a citizen of the United States, and a resident of the city of New York, in the 5 county and State of New York, have invented certain new and useful Improvements in Valve-Gears, of which the following is a specification.

My invention relates to the valve gear of 10 a reciprocating engine in which puppet valves are employed, and it consists in certain improvements which will first be described in connection with the accompanying drawings and will then be more specifically pointed out in the claims.

In the drawings—

Figure 1 is a transverse section of a steam engine cylinder with my improvement applied thereto, on line 1—1 Fig. 3—the line 20 of section of the steam valve appliances being in the vertical plane of the axis of the valve chamber or chest.

Fig. 2 is a section on line 2—2 of Fig. 1.

Fig. 3 is an end elevation partly in section of the valve chambers or chests, one at each end of the steam cylinder, the latter being in side elevation partly in longitudinal vertical axial section.

A is the steam cylinder. B are the cylindrical valve chests or chambers, one at each end of the steam cylinder and extending crosswise of, and substantially tangential to, the same. These chambers, together with the valves and valve gear appliances 30 contained in or connected with them, are the same at each end of the steam cylinder, so that a description of one will answer for both. C is a cage of cylindrical exterior removable from but closely fitted and held in 35 the valve chest B, which is machined out to receive it and is formed with an internal shoulder b against which the cage brings up. Within the cage is contained a double seated puppet valve V. The cage is provided with seats to engage the seats on the 40 valve V and with an axial tubular bearing or guide x for the valve spindle w, cast in one with the rear wall of the clearance chamber D. These parts may be of any usual or suitable construction, preferably such as shown 45 in my Patent No. 1,125,724 of January 19, 1915, in which form they here are represented. The inlet through which the steam enters the steam cylinder is indicated at e.

50 When the valve is open (in which posi-

sition it is shown in the drawings) steam passes from the inlet end of the valve chamber through the valve V and clearance chamber D in the cage, and thence through the inlet port e into the steam cylinder. 60

The cage C at its end opposite that which contains the valve extends beyond the spindle guide x out through the open end of the valve chest B and is provided with an annular laterally projecting flange c, which overlaps and fits snugly against the face of a corresponding flange d on the end of the latter, thus providing in a convenient manner for removably securing the cage in place in the valve chest by means of bolts and 70 nuts f as indicated in Fig. 3.

Diametrically crosswise of the cage, near its open end and cast in one therewith, is a tubular bearing g for the valve operating cam or tappet shaft S. This bearing is not continuous, but is composed of two portions which extend in an axial alinement with one another, from opposite sides of the cage toward the center, but do not meet, there being a space between their inner opposite ends 80 as shown more particularly in Figs. 2 and 3. This central space between the two is spanned by another tubular bearing h cast in one with the divided bearing g and cage C, the bore of which is in axial alinement with the valve spindle w, and is intended to receive the roller-carrier i which is secured to the end of the valve spindle as shown, and has mounted on it the pivoted anti-friction roller k which protrudes into the open space 85 between two opposed ends of the divided bearing g in position to be acted on by the cam or tappet shaft S, which latter has a longitudinal reciprocating movement imparted to it by suitable means, and is provided with a suitable cam surface k' to operate at proper intervals the valve spindle to move the valve against the stress of its opposed spring, as will be understood without further explanation. The divided bearing 90 g at its exterior opposite ends extends laterally through guide slots g' formed for their reception in the walls of the valve chest B as shown more particularly in Fig. 2. 95

The cam-bearing portions of the shaft S 100 are preferably separate from one another, there being one section s for each steam chest, detachably connected by an intervening section of shafting s' of smaller diameter as indicated in Fig. 3. This is the preferred 110

construction, although the shaft may be in one continuous piece if desired.

Under this arrangement the machining of all parts of the cage which require it, can be effected readily, accurately, in perfect alignment, and at little expense. The cage contains in a single casting all the parts that are needed to support and hold and guide the valve and all its operating appliances to 10 and including the valve operating cam shaft. And the valve together with its complete operating outfit can be mounted and assembled in that casting, before the latter is put into the steam chest.

15 The steam inlet end of each cylindrical valve chest B is closed by a head B' removably secured in place by bolts and nuts as customary. At the opposite end the steam chest is closed by the cage which protrudes 20 through and beyond it, their annular flanged ends being bolted together as hereinbefore described. The open end of the cage is fitted with a removable cap or shield c' of sheet metal or other suitable material to exclude 25 dust and dirt and other extraneous matter from the interior of the cage.

In the drawings I have illustrated my improvements in the structural form in which I prefer to embody them and which is designed 30 more particularly for use in connection with a steam engine of semi-uniflow type with a central exhaust, as indicated in the drawings. My improvements are however applicable to steam engines of other 35 types whether the ordinary reciprocating or the straight uniflow engine. The structural form in which they are embodied can also be varied. It is not indispensable, for example, in order to avail of the advantages 40 derived from the improved cage construction that the valve chest should occupy the particular position relatively to the steam cylinder in which it is shown in the drawings. Nor is it indispensable that the bearing 45 for the cam-shaft which is incorporated in the cage structure, should be a two-part or divided bearing of the particular construction represented. So, also, the valve operating cam-shaft, instead of being a 50 longitudinally reciprocating shaft, may be an oscillating or a rotating shaft with proper cam faces to meet the valve spindle during the oscillatory or rotary movement.

In these and other respects the construction can be varied to some extent without departure from the spirit of the invention. I do not limit myself, therefore, strictly to the structural details hereinbefore shown and described in illustration of my invention, but what I claim as new and desire to secure 60 by Letters Patent is as follows:

1. The combination with a steam cylinder and a valve chest, of the following elements 65 namely: a valve cage fitted and removably held in a seat of corresponding shape in the valve chest and formed with a clearance chamber and valve seats therein and an axial tubular bearing or guide for the valve spindle; a double seated spring-closed puppet valve in said clearance chamber provided with a valve spindle extending out through the said axial tubular bearing or guide; a bearing for the operating cam-shaft extending diametrically crosswise of the open end of, and carried by, the cage; 70 and a central tubular bearing carried by the said cam shaft bearing for the support and guidance of the roller end of the valve spindle which engages the cam operating shaft—all of the elements named being carried by, and movable as an entirety with, the valve cage.

2. A valve cage formed with a clearance chamber and valve seats therein, an axial tubular valve spindle guide integral with 85 the rear wall of the clearance chamber, a divided cam-shaft bearing integral with the cage composed of two tubular sections extending in axial alignment with each other from diametrically opposite sides of the 90 valve cage part way across the same, and a tubular bearing integral with and at right angles to the divided cam shaft bearing spanning the space between the inner adjoining ends of said divided cam shaft bearing and in axial alignment with the main spindle guide, to receive and support the roller end of the valve spindle; in combination with a steam cylinder, a valve chest in which the valve cage is removably housed, 95 a spring-closed valve and valve spindle, and an operating cam shaft substantially as and for the purpose hereinbefore stated.

In testimony whereof I affix my signature.

SIEGFRIED ROSENZWEIG.
